ATTORNEY.

UNITED STATES PATENT OFFICE.

JOHN PERSON, OF NETCONG, NEW JERSEY.

GUTTER FOR WINDSHIELDS.

1,375,104.

Specification of Letters Patent. Patented Apr. 19, 1921.

Application filed October 27, 1919. Serial No. 333,524.

To all whom it may concern:

Be it known that I, JOHN PERSON, a citizen of the United States, and a resident of Netcong, county of Morris, and State of 5 New Jersey, have invented certain new and useful Improvements in Gutters for Windshields, of which the following is a specification.

This invention relates to a gutter to be arranged on the bottom edge of the pane of a wind shield of an automobile. Wind shields as now made have usually fixed lower portion and an upper pane which swings and is usually projected outward so that it slants 10 forwardly and downwardly. In rainy weather the water runs down the wind shield and accumulates in rather large drops on the lower edge of the tilted pane, and due to the speed of the car these drops are blown 15 inside. Very little rain is blown in, but it is the accumulation of water on the edge of the shield that causes so much water to come in on those persons who occupy the front seat.

25 This invention is designed to provide a gutter that receives this water and conducts it to the sides of the wind shield, the gutter being open-ended and the tilting of the vehicle, due to the crown in the road, causing 30 the water to run to one side or the other, thus keeping the lower edge practically clear of dripping water.

The invention is illustrated in the accompanying drawing, in which Figure 1 is a 35 perspective view of part of a wind shield, the tilted pane being broken away, and the gutter being broken away also, to show its construction, the part of the gutter beyond the sectionized portion being shown in 40 dotted outline, and Fig. 2 is a section showing the bottom end of the pane and the gutter in section.

In the drawing 10 is the pane of a wind shield, which is usually provided with a 45 frame 11, the bottom end of the pane being without any frame portion because it is adapted to fit, the frame being provided with hinged or pivoted upper ends, as at 50 12, these elements being of different types and not being illustrated in detail herein as they form no part of this invention.

The strip 13 is arranged on the bottom edge of the pane and projects forwardly therefrom to the flange 14, thus co-acting 55 with the inclined pane of glass to form a gutter. The strip 13 can be of any desired

material, but is preferably made of soft rubber and is thus slightly elastic, which property is utilized to assist in holding it in position.

One means of holding this in position is by means of a groove or channel formed between the flanges 15 and 16, these flanges embracing the sides of the frame at the bottom edge thereof, as will be clearly evident from 60 the drawing. A strip made in this way, therefore, is F-shaped and the grip of the rubber flanges 15 and 16, in the case of light gutters, is sufficient for holding the gutter 65 in place.

I can, however, provide additional holding means in the form of clips 17, which 70 clips are usually provided with a top and bottom flange 18 and 19, these flanges going over the side members of the frame 11 and having a right-angled extension 20 which is riveted or otherwise secured to the end of the strip 13. The end 20 of the clip is usually 75 made narrower than the strip, so that the ends of the gutter are open, that is, there is 80 no projection in the channel of the gutter to interfere with the free passage of the water to the side edges of the shield and the water can thus run off without hindrance.

It will be evident that slight modifications 85 in the dimensions and in the form of the strip can be made without departing from the scope of the invention, and it will also be evident that various lengths of gutter 90 can be employed, but I prefer to make the gutter so that it extends from one side edge of the frame to the other side edge, so that the entire length of the bottom edge is thus protected from receiving the water that is deposited on the frame.

95 The use of this device permits the driving of a car in rainy weather without the annoyance of a closed wind shield, since a closed wind shield, when covered with drops of water, receiving the glare of an approaching car at night, prevents any view of the road, but with this device the wind shield can be left open, since there is no drip from the edge of it and a clear unobstructed view 100 of the road is possible.

105 I claim:

1. A gutter for the panes of wind shields comprising an elastic strip with parallel flanges along its top surface and adapted to engage the bottom of the two faces of the 110 panes, the strip extending beyond one of the flanges to form a gutter when the pane is

- inclined, and means on the ends of the strip for fastening the strip in place, whereby the strip is under a longitudinal tension and its flanges are thereby held against the pane.
- 5 2. A gutter for the panes of wind shields comprising an elastic strip with parallel flanges on its top surface so that a groove is formed at the rear of the strip for the bottom edge of the pane, and channeled clips 10 secured to the ends of the strip, said clips being adapted to engage the side edges of the wind shield so that the strip is under a longitudinal tension which holds the clips in place and forces the flanges in close engagement with the faces of the wind shield.
- 15 3. A gutter for the panes of wind shields

comprising a pair of opposed clips, each clip having top and bottom flanges and having a right-angled extension at the end to limit its movement on the side edges of a wind shield, 20 and an elastic strip secured to said extension and adapted by its tension to hold the clips in position and the strip against the bottom edge of the wind shield, said strip having a groove on its upper face near its back edge 25 to embrace the bottom edge of the pane and to also form a gutter to the front thereof.

In testimony that I claim the foregoing, I have hereto set my hand, this 20 day of October, 1919.

JOHN PERSON.
